UNITED STATES PATENT OFFICE.

FRANK C. RINSCHE, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

1,270,870.

Specification of Letters Patent.

Patented July 2, 1918.

Application filed August 18, 1913. Serial No. 785,376.

To all whom it may concern:

Be it known that I, FRANK C. RINSCHE, a citizen of the United States, residing at Detroit, in the county of Wayne and State of Michigan, have invented certain new and useful Improvements in Adding-Machines, of which the following is a specification.

This invention relates to the type of adding machines shown in prior Patents Nos. 10 1,016,501 and 1,023,168 issued February 6, 1912, and April 16, 1912, respectively. In these machines the turning of wheels to effect registration is done by return of spring-actuated levers after displacement thereof 15 by depressible keys and release of the latter. The keys are arranged in rows each row made up of nine keys numbered from 1 to 9 and constructed and arranged to act upon the associated registering lever at varying 20 distances from its pivot, the 9-key acting nearest the pivot, the 8-key a step farther away and so on. Upon reference to said prior patents it will be observed that the acting lugs of the keys are not normally in 25 engagement with the lever, the latter being stopped in its return movement by contact of its forward end with a cross bar, and it will further be observed that the lugs of the lower denomination keys 1 and 2 are spaced 30 farther from the lever than the lugs of other keys. This is so because of a purpose to arrange for uniform "dip" or extent of depression of all of the keys while at the same time preserving a compact arrangement of 35 the keys with their tops spaced slightly and uniformly from each other from front to rear. The keys are normally upheld by comparatively light springs and it has been found that, owing to the relatively slight resistance to depression of the lower denomination keys prior to their striking the lever, there may be a failure to fully depress these 40 keys against the considerably greater resistance offered by the relatively strong spring 45 which upholds the lever. The lost motion between the lugs of the other keys and the lever is so slight that the variation in resistance to their depression does not have to be taken into account, the extent of their depression against the lighter resistance being 50 so very short that the sensation is that of applying finger pressure against the heavier resistance from the beginning. In case of 55 the lower denomination keys however the

extent of depression against the light resistance is of such extent as to be distinctly noticeable so that there is an inclination to relax the pressure when the heavier resistance is encountered.

The purpose of the present invention is to 60 compensate for this greater extent of movement of the lower denomination keys against the light resistance so that there will be no noticeable increase in resistance such as to incline the operator to relax the finger pressure and to accomplish this without adding any weight to the registering lever, and in 65 fact without attaching any parts to that lever, so that its action is not affected at all.

In the form of embodiment of my invention here shown I depart from the arrangement of increased spacing of the lugs of the lower denomination keys from the registering lever and do not have lugs upon the key 70 stems of these keys but upon separate pieces 75 between which and the keys there is lost motion corresponding in extent with that heretofore allowed between the lugs and the lever.

In the drawings which accompany and form part of this specification Figure 1 represents in sectionalized right-side elevation a machine of the type shown in said prior patents, having incorporated therein parts for carrying out my invention; Fig. 2 is a similar view showing the 1-key depressed; Fig. 3 is a perspective view of this key detached; Fig. 4 is a similar view of the key turned over and with the lug-bearing piece left off and Fig. 5 is a perspective view of the key 80 complete in reversed position as compared 85 with Fig. 3.

In view of the complete disclosures in the aforesaid prior patents, it will be unnecessary to enter into any detailed description of the machine proper or to do more than 90 designate a few of the parts thereof with which the new parts for carrying out the present invention are more intimately associated. D designates key stems of one of the rows of keys and d the relatively light 100 springs which normally uphold these keys, and the reference letter F designates a registering lever associated with the keys and normally upheld by a relatively-strong spring F², with the front end of the lever 105 against a frame cross rod a⁴ as illustrated in Fig. 1. d² designates lugs struck out from the stems of the seven keys counting from

the right of Fig. 1, said lugs being slightly spaced from the upper edge of the lever under normal conditions.

In carrying out my present invention, I specially construct the 1 and 2-keys, their stems 10 not being formed with lugs as heretofore though they do have narrowed lower portions surrounded by the light springs *d* as before and are also longitudinally slotted 10 as at 10^a for the passage of the stop rods *a* which limit the downward movement of these keys as in the prior constructions. There is mounted against one side of each of these key stems 10 a slide plate 11 (Fig. 5) slotted at 11^a to accommodate the cross rod *a*, the slot being elongated to provide for longitudinal movement of this plate upon the key stem. The plate has an additional slot 11^b for the same purpose and is held against the key stem by headed rivets 10^b fastened in the key stem and engaging the slots respectively as clearly shown in Fig. 5. At the lower end of the plate a lug 11^c is struck out and extends past the front end of the key stem and over the registering lever F. A spring 12 connects an ear 11^d of said plate with an ear 10^c of the key stem and this spring normally pulls the plate down so that the upper end of the slot 11^b is engaged 25 with the upper one of the headed studs 10^b.

Normally the lugs 11^c are closely adjacent the upper edge of the lever F (Fig. 1) so that there is no appreciable lost motion between the lugs and the lever. However, there is lost motion between the key stems and the slide pieces so that the keys may be depressed a distance without displacing the registering lever F. This corresponds with the distance through which these lower denomination keys would be depressed in the prior constructions before their lugs would encounter the upper edge of the lever F. In the present instance there is added to the resistance offered by the springs *d* to the depression of the keys, the resistance offered by the springs 12. It will of course be understood that the latter springs are inferior to the springs F² which uphold the registering levers. Therefore upon depression of one 45 of these lower denomination keys the lever F will not yield at first but the spring 12 will be stretched while the lug 11^c stands in contact with the upper edge of the lever F and the upper stud 10^b is traversing the slot 50 11^b. When said stud reaches the lower end of said slot the continued finger pressure affects the slide piece just as though it had become integral with the key stem, and the lug 11^c then depresses the lever F as illustrated in Fig. 2.

While necessarily the spring 12 is inferior to the spring F², yet the combined resistance of the spring 12 and the spring *d* to depression

of the key approximates the resistance offered by the spring F² to the continued depression of the key, so that there is no noticeable increase in resistance when the lever F begins to be displaced and therefore the operator has no inclination to relax finger pressure and fail to fully depress the key. 65 Of course when the key stem has taken up the lost motion between it and the slide piece there is no further stretching of the spring 12 and consequently the resistance to the continued depression of the key when displacing 70 the lever F is the same as in the prior construction, to wit, that offered by the spring F² and the slight resistance offered by the spring *d*.

It is to be noted that in accomplishing the 80 above result I avoid mounting any parts upon the registering lever and I thus gain the advantage of not increasing the weight of the lever or resistance to the action of the spring F². There are also advantages in 85 convenience of assembling, by having all of the compensating mechanism a part of the key structure. In these respects the invention is to be distinguished from the prior inventions of Roy L. Burd (application No. 90 783,701 filed August 8, 1913) and Walter J. Pasinski (application No. 783,703 filed August 8, 1913).

While the above-described construction is well adapted to carry out my object, I wish 95 it understood that my invention is susceptible of embodiment in other forms than that here shown.

I claim:

1. In a machine of the class described the 100 combination of a registering lever; a series of keys constructed and arranged to act upon said lever at increasing distances from the latter's pivot and with lost motion as to certain of said keys which act at the greater distances; and compensating means applied directly to the said certain key or keys only whereby to create substantially uniform resistance to their depression though displacement of the lever by such keys is less proportionately to the extent of their depression than is displacement of said lever by other keys proportionate to similar extent of depression of the latter, such other keys acting independently of said compensating 105 means.

2. In a machine of the class described the combination of a registering lever; a series of keys constructed and arranged to act upon said lever at increasing distances from the 120 latter's pivot and with lost motion as to certain of said keys which act at the greater distances; and spring-held lost-motion contact pieces mounted upon certain of the keys which act at the greater distances, substantially as and for the purpose described.

3. In a machine of the class described, the combination of a registering lever, a series of keys constructed and arranged to act upon said lever at increasing distances from its 5 pivot; and spring-held lost-motion contact pieces slidably mounted upon certain of the

keys which act at the greater distances, substantially as and for the purpose described.
